UNSYMMETRICAL ELECTRIC WAVE FILTER

Wilhelm Cauer, Gottingen, Germany

Application November 23, 1933, Serial No. 699,391
In Germany November 10, 1932

12 Claims. (Cl. 178—44)

My invention relates to electric, four-terminal networks and more particularly to electric-wave filters adapted for the selection and propagation of electromagnetic signals of prescribed ranges 5 of frequency.

In Letters Patent 1,989,545, issued January 29, 1935, I have disclosed and claimed symmetrical wave filters, as well as such unsymmetrical filters as are equivalent to a symmetrical filter connected in series with a transformer, or with a phase-correction circuit, or both.

One of the objects of the present invention is to provide new and improved unsymmetrical, four-terminal networks that are not equivalent to a 15 symmetrical, four-terminal network in series with an ideal transformer.

A further object is to provide unsymmetrical wave filters of the above-described character for which the determinant of the characteristic 20 matrix is a constant. Such a filter will hereinafter be referred to as a K-D-filter.

Another object of the invention is connected with the use, in K-D-filters, of T-parameters derivable from known Tschebyscheff-parameters.

Other objects of the invention are to provide 25 K-D-filters without ideal transformers, as well as novel networks containing inductive couplings.

A further object of the invention is to provide unsymmetrical wave filters, and more particularly 30 K-D-filters, having all the advantages of symmetrical filters. As filters of the above-described character, furthermore, are of more general nature than symmetrical filters, it is possible, with their aid, to solve problems that are sometimes 35 not capable of solution with the use of symmetrical networks alone.

Other and still further objects will be explained hereinafter, and will be particularly pointed out in the appended claims, it being understood that 40 I intend, by suitable expressions in the claims, to specify all the novelty that the invention may possess.

The invention will now be explained in connection with the accompanying drawing, in which 45 Figs. 1 and 2 are diagrammatic views illustrating four-terminal, symmetrical filters obtained from an unsymmetrical network by reflecting the same and connecting the network and its reflection in series; Fig. 3 is a diagrammatic view of an unsymmetrical, high-pass, K-D-filter circuit arranged according to one form of the present invention; Fig. 4 is a diagram showing plots or curves of attenuation characteristics of the filter circuits illustrated in Fig. 3; and Fig. 5 is a similar diagram showing plots or curves of corre-

sponding image-impedance characteristics.

In Fig. 3, there is shown a four-terminal network, the pair of input terminals being shown at 1, 1' and the pair of output terminals at 2, 2'. For present purposes, this network may be considered to represent any unsymmetrical, four-terminal network, and it is proposed to show how to obtain its matrix.

Letting E_1 represent the complex voltage at the input terminals 1, 1'; I_1 represent the complex current at the input terminals 1, 1'; E_2 represent the complex voltage at the output terminals 2, 2'; and I_2 represent the complex current at the output terminals 2, 2'; and letting

$$\omega = 2\pi f$$

$$\lambda = i\omega$$

and

$$i = \sqrt{-1}$$

where ω , the pulsatance, represents the frequency parameter, the frequency being represented by f ; then there are two linear equations between these voltages and currents, as follows:

$$\begin{aligned} E_1 &= Z_{11}(\lambda) I_1 + Z_{12}(\lambda) I_2 \\ E_2 &= Z_{12}(\lambda) I_1 + Z_{22}(\lambda) I_2 \end{aligned}$$

where Z_{11} , Z_{12} and Z_{22} represent rational functions of λ , to be evaluated according to the requirements of the particular problem in hand. To 30 make a good approximation to zero attenuation in the transmitting bands, it is necessary that the resistances be nearly zero. In the following portion of this specification, the resistances will be wholly neglected for this reason and also because 35 it will simplify the discussion without in reality detracting from the generality of the method. If the resistances then be neglected, Z_{11} and Z_{22} will have special values of reactances, which are characteristics of two-terminal networks.

$$\begin{pmatrix} Z_{11} Z_{12} \\ Z_{12} Z_{22} \end{pmatrix}$$

is the characteristic matrix of the four-terminal network.

It may be assumed, without essentially restricting the generality of the problem, that a receiver and a transmitter having equal resistances R are connected together by an electric wave-filter. It 50 will be understood, of course, that the invention is not exclusively restricted to the case of equal resistances at the ends of the filter, for the case of unequal resistances can be reduced to the case of equal resistances by a serial connection of the 55

filter with an ideal transformer, or by a network equivalent to it.

It will be convenient to deal, not with the functions Z_{11} , Z_{12} and Z_{22} themselves, but with the reduced impedance functions

$$z_{11} = \frac{Z_{11}}{R}$$

$$z_{12} = \frac{Z_{12}}{R}$$

10 and

$$z_{22} = \frac{Z_{22}}{R}$$

15 which are also rational functions of λ .

The design of constructing a filter can be always divided in two parts: first, to obtain a suitable, realizable, characteristic matrix of the functions z_{11} , z_{22} and z_{12} ; and secondly, to construct the physical network that corresponds to that matrix. The most important function for the characterization of a filter is the working or total attenuation, represented by A . This will be defined as

$$25 A = \ln \left| \frac{I}{I'} \right|$$

I denoting the current which would flow in the receiving apparatus if the sending apparatus and the receiving apparatus were immediately connected together; and I' denoting the corresponding current that would flow if the wave-filter were interposed between them. In the general case, A is the following function of z_{11} , z_{22} and z_{12} :

$$35 (1) A = \ln \left| \frac{(z_{11}+1)(z_{22}+1)-z_{12}^2}{2z_{12}} \right|$$

In the special case of the K-D-filters, characterized by

$$40 \Delta = \left| \frac{z_{11} z_{12}}{z_{12} z_{22}} \right| = 1$$

this reduces to

$$45 (1a) A = \ln \left| \frac{z_{11} + z_{22} + 2}{2z_{12}} \right|$$

From these equations, it follows that $A = \infty$ if $z_{12} = 0$; further, that $A = 0$, if

$$W_1 = R \sqrt{\frac{z_{11}}{z_{22}}} \cdot \Delta = R$$

50 and

$$W_2 = R \sqrt{\frac{z_{22}}{z_{11}}} \cdot \Delta = R$$

where W_1 represents the image impedance at the input terminals 1, 1', and W_2 represents the 55 image impedance at the output terminals 2, 2'. That these two latter conditions are necessary and sufficient for ideal transmission follows also without the use of Equation (1), from the fact that a maximum transfer of energy from a sending apparatus with real internal resistance and a given electromotive force to a receiving apparatus joined thereto can take place only if this receiving resistance is equal to the internal resistance of the sending apparatus.

60 It follows from the formulas

$$W_1 = R \sqrt{\frac{z_{11}}{z_{22}}} \cdot \Delta$$

and

$$W_2 = R \sqrt{\frac{z_{22}}{z_{11}}} \cdot \Delta$$

70 that the condition that the determinant of the characteristic matrix shall be a constant,

means physically that the left-side, image impedance, or the surge impedance, W_1 , is R^2 times the reciprocal of the right-side image impedance W_2 :

$$5 W_1 = \frac{R^2}{W_2}$$

as appears from Fig. 5. This will hereinafter be referred to as the "constant determinant" condition.

10 As an ideal transmission in the complete frequency ranges is required, in the practical case, networks having reactances only are applicable. As z_{11} and z_{22} are reactances, they can have only discrete poles alternating always with the zeros. 15 The requirement of a very high attenuation in a complete frequency range can only be fulfilled, therefore, by having

$$z_{12} = 0$$

20 from which it follows that this requirement is necessary as well as sufficient.

In accordance with a feature of the invention, the construction of general, unsymmetrical filters is reduced to that of symmetrical filters. 25 In Fig. 1, an unsymmetrical filter F is shown arranged in series with a filter F' , a reflection thereof. The filters F and F' are identical, the input and output terminals, however, being interchanged. From the unsymmetrical filter F there is thus produced a symmetrical four-terminal 30 network, which is a symmetrical filter, as appears from the "Siebschaltungen" (V. D. I.-Verlag 1931). For, it follows, from

$$z_{12} = 0$$

35 in the attenuation ranges of F , that the left half of the filter alone attenuates. The complete symmetrical filter will therefore do the same. Furthermore, the decisive function

$$\sqrt{\frac{z_1}{z_2}}$$

40 of the four-terminal attenuation or attenuation constant A_1 of a symmetrical filter, being approximately 1 in the attenuation ranges, will be obtained by

$$45 (2) D = \sqrt{\frac{z_{11} z_{22}}{\Delta}}$$

from which it follows that

$$z_{12} = 0$$

50 is the same thing as having

$$D = 1$$

55 On the other hand, W_1 is the image impedance of the symmetrical filter illustrated in Fig. 1; that is, it is the function

$$\sqrt{z_1 z_2}$$

60 in symmetrical wave filters; and W_2 is the image impedance of symmetrical, four-terminal networks illustrated in Fig. 2, obtained, similarly, from reflection of the filter F on the other side, and arrangement in series. It therefore follows 65 from the theory of symmetrical filters, as described in the aforesaid Letters Patent, that, according to the type of filter (whether low-pass, high-pass, band-pass and band-elimination or low-and-high-pass filter), only certain classes of 70 functions of the frequency parameter λ can be used. But the selection of these classes, and of the parameters in the different classes, is no more arbitrary than it is in the case of the symmetrical filters, since the question is now of symmetrical 75

filters of the special structure illustrated in Fig. 1 or Fig. 2.

To restrict further the classes and parameters, one may employ my theorem concerning the necessary and sufficient conditions for the realization of any arbitrary unsymmetrical, reactance, four-terminal network (see "Reaktanz theorem" of W. Cauer, Sitzungsberichte der preussischen Akademie der Wissenschaften, Berlin, 1931).

10 This theorem reads:

In order that a quadratic, symmetrical matrix

$$Z(\lambda) = (Z_{st})$$

15 with no rows may be assumed as the characteristic matrix of a reactance, 2n-terminal network, it is necessary that the associate quadratic form

$$\sum_{s,t=1}^n Z_{st} I_s I_t$$

20 for each real system of values

$$I_1, I_2, \dots, I_n$$

shall satisfy the conditions which are true for 25 two-terminal reactances. Elements of such matrices, and of such matrices only, can be written in the form

$$30 (3) \quad Z_{st} = \lambda \sum_{r=1}^m \frac{h_{st}^{(r)}}{\lambda^2 + b_r} + h_{st}^{(\infty)} \lambda + h_{st}^{(0)} \lambda^{-1}$$

where

$$35 (4) \quad \sum_{s,t=1}^n h_{st}^{(r)} I_s I_t \geq 0 \quad (r=0, 1, 2, \dots, m, \infty)$$

$$b_r > 0 \quad (r=1, 2, \dots, m)$$

The same conditions are sufficient if $n-1$ ideal 40 transformers are added to the reactances.

In the present case, n is to be chosen equal to 2. 45 The construction of general, unsymmetrical wave filters follow readily as a result of these conditions. W_1 , W_2 and D may be arbitrarily selected—according to the type and the cut-off (limiting) frequencies of the filter—from the known classes for

$$\sqrt{Z_1 Z_2}$$

and

$$50 \quad \sqrt{\frac{Z_2}{Z_1}}$$

Then Z_{11} results as $W_1 D$, Z_{22} as $W_2 D$ (both of them realizable reactances) and

$$55 \quad R^2 \Delta = Z_{11} Z_{22} - Z_{12}^2$$

as $W_1 W_2$. It is next in order to find out if

$$Z_{12} = \sqrt{W_1 W_2 (D^2 - 1)}$$

60 is not contradictory to the above conditions of realization, and the choice of the classes and parameters has to be undertaken with this in mind.

Of the numerous new unsymmetrical wave-

filters thus obtainable, it is desired to make special note of the K-D-filters, where

$$\Delta = 1.$$

A numerical, concrete example will make this 6 more clear. Here,

$$Z_{12} = R \sqrt{D^2 - 1}.$$

Because

$$\Delta = 1,$$

10

all the above conditions of realization are fulfilled if the root in Z_{12} becomes a real, and if Z_{12} is a rational function of λ . For Z_{11} and Z_{22} become reactances in the same way as Z_1 and Z_2 in the case of symmetrical filters (see my prior Patent No. 1,989,545), and the Formulae (3) for Z_{11} and Z_{22} together with the restrictions (4) state only that Z_{11} and Z_{22} are reactance functions. Furthermore, if Z_{12} becomes a real and rational function of λ , Z_{12} must have the form (3) and the following relation must exist:

$$(5) \quad h_{11}^{(r)} h_{22}^{(r)} - h_{12}^{(r+2)} = 0 \quad (r=0, 1, 2, \dots, m, \infty).$$

Condition (4) is, therefore, satisfied; else Δ could not be independent of λ . The classes of functions of the following Table I for

$$D = \sqrt{Z_{11} Z_{22}}$$

are then possible. The invention is applicable to 30 other filters of the LP, HP, BP and BE type, as well as to filters of higher types. They may be derived by the rules hereinafter given immediately after the formulas for W_1 for the band-elimination filters (BE). 35

TABLE I

$$D = \sqrt{Z_{11} Z_{22}} \text{ for K-D-filters } (Z_{11} Z_{22} - Z_{12}^2 = R^2).$$

Low-pass-filters (LP)

$$(1/2) \quad \frac{\sqrt{\lambda^2 + \omega_1^2}}{m \lambda} \\ (3/2) \quad \frac{(\lambda^2 + \omega_3^2) \sqrt{\lambda^2 + \omega_1^2}}{m \lambda (\lambda^2 + \omega_3^2)} \\ \vdots \\ (2_{n+1/2}) \quad \frac{(\lambda^2 + \omega_{a,2n}^2) \dots (\lambda^2 + \omega_{a,2}^2) \sqrt{\lambda^2 + \omega_1^2}}{m \lambda (\lambda^2 + \omega_{a,2n-1}^2) \dots (\lambda^2 + \omega_{a,1}^2)} \quad 50$$

High-pass-filters (HP)

$$(\alpha/2) \quad \frac{\sqrt{\lambda^2 + \omega_1^2}}{\mu} \\ (\gamma/2) \quad \frac{\sqrt{\lambda^2 + \omega_1^2} (\lambda^2 + \omega_{\beta}^2)}{\mu (\lambda^2 + \omega_{\beta}^2)} \\ \vdots \\ (2_{n+1/2}) \quad \frac{\sqrt{\lambda^2 + \omega_1^2} (\lambda^2 + \omega_{\alpha,2}^2) \dots (\lambda^2 + \omega_{\alpha,2n}^2)}{\mu (\lambda^2 + \omega_{\alpha,1}^2) \dots (\lambda^2 + \omega_{\alpha,2n-1}^2)} \quad 60$$

Band-pass-filters (BP)

$$(2/2) \quad \frac{\sqrt{\lambda^2 + \omega_{-1}^2} \sqrt{\lambda^2 + \omega_1^2}}{m (\lambda^2 + \omega_0^2)} \\ (6/2) \quad \frac{\sqrt{\lambda^2 + \omega_{-1}^2} (\lambda^2 + \omega_{-b}^2) (\lambda^2 + \omega_b^2) \sqrt{\lambda^2 + \omega_1^2}}{m (\lambda^2 + \omega_{-a}^2) (\lambda^2 + \omega_0^2) (\lambda^2 + \omega_a^2)} \\ \vdots \\ (4_{n+2/2}) \quad \frac{\sqrt{\lambda^2 + \omega_{-1}^2} (\lambda^2 + \omega_{-a,2}^2) \dots (\lambda^2 + \omega_{-a,2n}^2) (\lambda^2 + \omega_{a,2}^2) \dots (\lambda^2 + \omega_{a,2n}^2) \sqrt{\lambda^2 + \omega_1^2}}{m (\lambda^2 + \omega_{-a,1}^2) \dots (\lambda^2 + \omega_{-a,2n-1}^2) (\lambda^2 + \omega_0^2) (\lambda^2 + \omega_a^2) \dots (\lambda^2 + \omega_{a,2n-1}^2)} \quad 70$$

65

$$(2/2) \quad \frac{\sqrt{\lambda^2 + \omega_{-1}^2} \sqrt{\lambda^2 + \omega_1^2}}{m (\lambda^2 + \omega_0^2)}$$

$$(6/2) \quad \frac{\sqrt{\lambda^2 + \omega_{-1}^2} (\lambda^2 + \omega_{-b}^2) (\lambda^2 + \omega_b^2) \sqrt{\lambda^2 + \omega_1^2}}{m (\lambda^2 + \omega_{-a}^2) (\lambda^2 + \omega_0^2) (\lambda^2 + \omega_a^2)}$$

$$\vdots$$

$$(4_{n+2/2}) \quad \frac{\sqrt{\lambda^2 + \omega_{-1}^2} (\lambda^2 + \omega_{-a,2}^2) \dots (\lambda^2 + \omega_{-a,2n}^2) (\lambda^2 + \omega_{a,2}^2) \dots (\lambda^2 + \omega_{a,2n}^2) \sqrt{\lambda^2 + \omega_1^2}}{m (\lambda^2 + \omega_{-a,1}^2) \dots (\lambda^2 + \omega_{-a,2n-1}^2) (\lambda^2 + \omega_0^2) (\lambda^2 + \omega_a^2) \dots (\lambda^2 + \omega_{a,2n-1}^2)} \quad 75$$

Band-elimination-filters (BE)

(b/2)	$\frac{\sqrt{(\lambda^2 + \omega_{-1}^2)(\lambda^2 + \omega_1^2)}}{\mu\lambda}$	5
(f/2)	$\frac{(\lambda^2 + \omega_{-\beta}^2)\sqrt{(\lambda^2 + \omega_{-1}^2)(\lambda^2 + \omega_1^2)(\lambda^2 + \omega_{\beta}^2)}}{\mu\lambda(\lambda^2 + \omega_{-\alpha}^2)(\lambda^2 + \omega_{\alpha}^2)}$	5
⋮	⋮	⋮
(a _{4n+2/2})	$\frac{(\lambda^2 + \omega_{-\alpha,2n}^2) \dots (\lambda^2 + \omega_{-\alpha,2}^2)\sqrt{(\lambda^2 + \omega_{-1}^2)(\lambda^2 + \omega_1^2)(\lambda^2 + \omega_{\alpha,2}^2)} \dots (\lambda^2 + \omega_{\alpha,2n}^2)}{\mu\lambda(\lambda^2 + \omega_{-\alpha,2n-1}^2) \dots (\lambda^2 + \omega_{-\alpha,2}^2)(\lambda^2 + \omega_{\alpha,1}^2) \dots (\lambda^2 + \omega_{\alpha,2n-1}^2)}$	10

In this table, ω_1 , for example, is identical with α , α_3 with γ etc., a_2 with b , a_6 with f , etc. The numerator in the signs for the classes, for example, 3 in 3/2 signifies with which class from the "Siebschaltungen" the concerned class is identical. The symbolical factor 1/2 is to make it obvious that the attenuation of the unsymmetrical filter F (illustrated in Figs. 1 and 2) is only half of the attenuation of the symmetrical filter with attenuation characteristic D. m and μ signify positive constants, $\omega_{\alpha,1}$, $\omega_{\alpha,2}$ etc. are resonance and anti-resonance frequencies, following, as written, from left to right in their order of magnitude. This is true also for Table II—(for example, $\omega_d < \omega_c < \omega_b < \omega_a$ in class 5/2). Unlike the corresponding case with symmetrical filters, however, these resonance and anti-resonance frequency parameters cannot be chosen with perfect freedom, as far as the given inequalities will allow, but certain equalities, which will now be discussed, ought to exist between them. These equalities make it possible for Z_{12} to become a real, rational function of λ .

With restrictions again to LP, HP, BP and BE filters, any of the

$$\sqrt{Z_1 Z_2}$$

—classes of symmetrical filters can be chosen from the Tables I-IV of the "Siebschaltungen", no restriction at all existing for W_1 between the arbitrary parameters except the named inequalities. These classes for W_1 are written down in

the following Table II. It is to be borne in mind that

$$W_2 = \frac{R^2}{W_1}$$

TABLE II

$$\frac{W_1}{R} = \sqrt{\frac{Z_{11}}{Z_{22}}} = \frac{R}{W_2}$$

for filters with constant determinant

$$(Z_{11}Z_{22} - Z_{12}^2 = R^2)$$

(f)	$\frac{\mu(\lambda^2 + \omega_{-\alpha}^2)(\lambda^2 + \omega_{\alpha}^2)}{\mu\sqrt{(\lambda^2 + \omega_{-\beta}^2)\sqrt{(\lambda^2 + \omega_{-1}^2)(\lambda^2 + \omega_1^2)}(\lambda^2 + \omega_{\beta}^2)}}$	65

Band-elimination-filters (BE)

$$\begin{aligned}
 (1) \quad & m \frac{\sqrt{\lambda^2 + \omega_{-1}^2}}{\sqrt{\lambda^2 + \omega_1^2}} \\
 (2) \quad & m \frac{\lambda^2 + \omega_0^2}{\sqrt{\lambda^2 + \omega_{-1}^2} \sqrt{\lambda^2 + \omega_1^2}} \\
 (3) \quad & m \frac{\sqrt{\lambda^2 + \omega_{-1}^2} (\lambda^2 + \omega_a^2)}{(\lambda^2 + \omega_{-a}^2) \sqrt{\lambda^2 + \omega_1^2}} \\
 (4) \quad & m \frac{(\lambda^2 + \omega_{-a}^2) (\lambda^2 + \omega_a^2)}{\sqrt{\lambda^2 + \omega_{-1}^2} (\lambda^2 + \omega_a^2) \sqrt{\lambda^2 + \omega_1^2}} \\
 (5) \quad & m \frac{\sqrt{\lambda^2 + \omega_{-1}^2} (\lambda^2 + \omega_{-b}^2) (\lambda^2 + \omega_b^2)}{(\lambda^2 + \omega_{-a}^2) (\lambda^2 + \omega_b^2) \sqrt{\lambda^2 + \omega_1^2}} \\
 (6) \quad & m \frac{(\lambda^2 + \omega_{-a}^2) (\lambda^2 + \omega_b^2) (\lambda^2 + \omega_a^2)}{\sqrt{\lambda^2 + \omega_{-1}^2} (\lambda^2 + \omega_{-b}^2) (\lambda^2 + \omega_b^2) \sqrt{\lambda^2 + \omega_1^2}}
 \end{aligned}$$

$$\begin{aligned}
 (2n-1) \quad & m \frac{\sqrt{\lambda^2 + \omega_{-1}^2} (\lambda^2 + \omega_{a,1}^2) (\lambda^2 + \omega_{a,2}^2) \dots (\lambda^2 + \omega_{a,2n-2}^2)}{(\lambda^2 + \omega_{a,1}^2) (\lambda^2 + \omega_{a,3}^2) \dots (\lambda^2 + \omega_{a,2n-3}^2) \sqrt{\lambda^2 + \omega_1^2}} \\
 (2n) \quad & m \frac{(\lambda^2 + \omega_{a,1}^2) (\lambda^2 + \omega_{a,3}^2) \dots (\lambda^2 + \omega_{a,2n-1}^2)}{\sqrt{\lambda^2 + \omega_{-1}^2} (\lambda^2 + \omega_{a,2}^2) \dots (\lambda^2 + \omega_{a,2n-2}^2) \sqrt{\lambda^2 + \omega_1^2}}
 \end{aligned}$$

The parameters of the D-classes ought to be determined in such a manner that Z_{12} becomes real and rational. The following method for attaining this result presents itself. The general rule is true that if w_1 and w_2 are possible

$$\sqrt{\frac{Z_2}{Z_1}} = \text{classes}$$

of the same type (for example, LP) of symmetrical filters, this is true also for

$$(6) \quad w_3 = \frac{1 + w_1 w_2}{w_1 + w_2}$$

Then w_3 (as well as

$$\frac{1}{w_3}$$

has as rejector frequencies (frequencies at which the attenuation is infinite) the rejector frequencies of w_1 as well as those of w_2 . A rejector frequency of w_1 is a frequency for which

$$w_1 = 1,$$

a rejector frequency of w_2 is a frequency for which

$$w_2 = 1$$

and a rejector frequency of w_3 is a frequency for which

$$w_3 = 1.$$

If one chooses

$$w_1 = w_2,$$

w_3 obtains double rejector frequencies. By such combinations, such D-classes (see Table 1) can be found with such parameters that all rejector frequencies are double and

10

$$Z_{12} = \sqrt{Z_{11} Z_{22} - 1}$$

becomes rational and real.

Good filters have the quality that their resonance and anti-resonance-frequencies are closer and closer together as the limiting frequencies are approached. A special choice of such para-

15

meters which comprises, in addition to the postulate of physical realizability (that is, that Z_{12} shall be real and rational), even further restrictions, resulting in obtaining most valuable filters of a certain class, are the T-parameters. These parameters are nearly identical with the Tscheby-scheff-parameters defined in the "Siebschaltungen". The only difference is that the constant factor m or μ is chosen in a different way, so that the largest value of

$$\sqrt{Z_{11} Z_{22}}$$

in the intervals of approximation (T-intervals) is 1. Then the smallest value in the intervals of approximation is H^{-2} or Θ^{-2} ; or, expressed otherwise: the breadth of the region where

$$\ln \sqrt{Z_{11} Z_{22}}$$

40

varies in the T-intervals is $2 \ln H$ or $2 \ln \Theta$. This is illustrated by Curve 2, Fig. 4. It thus results that all rejector frequencies are double, so that Z_{12} becomes rational. The T-parameters can be found from the following Table III.

50

TABLE III

T-Parameters

LP Class	BP Class	m	a	b	c	d	$\dots$	$\sqrt{1 - H^{-4}}$
1/2	2/2	1	---	---	---	---	---	k^{-1}

	$\vdots$	$\vdots$	$\vdots$	$\vdots$	$\vdots$	$\vdots$	$\vdots$	$\vdots$	$\vdots$
15	HP	$\omega_\alpha = \alpha \omega_1, \omega_\beta = \beta \omega_1, \dots$							
	BE	$\omega = \omega^2 = \omega_{-1} \omega_1 \pm \frac{1}{2} (\omega_1 - \omega_{-1})^2 \alpha^2 \left(\sqrt{1 + \frac{4 \omega_{-1} \omega_1}{(\omega_1 - \omega_{-1})^2 \alpha^2}} \pm 1 \right)$, instead of α also $\beta, \gamma, \dots$							

In Table III, sn signifies the Jacobian elliptic function, $k^{-1} < 1$, or $\kappa < 1$ is the modulus, and K or K is the complete elliptic integral of the first kind. As can be seen, all parameters appearing depend on but a single independent parameter, namely, k^{-1} or κ which has to satisfy only the single condition that it be positive and less than 1. An interesting property of these T-parameters is that the places $\Omega_{\min}$ of the equal high minima of the attenuation, expressed by normalized frequencies, are given by the ratio of the normalized limits k (or κ) of the T-intervals and the normalized resonance frequencies (zeros)

$$b, d, \dots \text{ (or } \beta, \delta, \dots \text{)}$$

of the attenuation function

$$\sqrt{Z_{11} Z_{22}}$$

(or, in other words, of each of the open-circuit impedances Z_{11}, Z_{22} in the pass-band or -bands). A further property of the T-parameters, which can be easily checked is that to each normalized anti-resonance frequency

$$a, c, e, \dots \text{ (or } \alpha, \gamma, \epsilon, \dots \text{)}$$

of the open-circuit impedances in the pass-band or -bands, there corresponds a place of infinite attenuation such that the product of the corresponding (normalized) frequencies is equal to the normalized frequency k (κ) of the limit of the T-interval. This connecting law also applies when the frequency is zero or infinite, it being possible to associate with the anti-resonance frequency zero of the open circuit impedances of a low pass-filter, a place of infinite attenuation at a frequency of infinity, and conversely with the high-pass filter and analogously in the case of BP and BE filters. This will be verified in the numerical example below.

The connection between the normalized frequencies and the ordinary pulsatances ω is given for the different types of filters (see also "Siebschaltungen" Table XI) by the following formulas:

for LP and HP:

$$\omega = \Omega \omega_1$$

for BP and BE:

$$\omega^2 = \omega_{-1} \omega_1 \pm \frac{1}{2} (\omega_1 - \omega_{-1}) \Omega^2 \left(\sqrt{1 + \frac{4 \omega_{-1} \omega_1}{(\omega_1 - \omega_{-1})^2 \Omega^2}} \pm 1 \right)$$

where

$$\Omega = \frac{\omega^2 - \omega_{-1} \omega_1}{(\omega_1 - \omega_{-1}) \omega}$$

In the classes $3/2, \gamma/2$ and $f/2$, in which only one free parameter appears, except the limiting frequencies, each physically possible system of parameters is a system of T-parameters. It is to

be observed, furthermore, that the parameters realized in practice may, of course, deviate somewhat from the exact values given in Table III. In practice, the admissible tolerances affecting a modification of the computed minimum attenuation should be not more than 10 percent.

The attenuation constant A_1 of the K-D-filter is defined as the half of the attenuation constant of the appropriate symmetrical filter obtained by doubling (in the "Siebschaltungen" the same letter A_1 is used). In the case of T-parameters, the minimum value of A_1 is given in the T-intervals by the formula

$$A_1 = \frac{1}{2} \ln \frac{H^2 + 1}{H^2 - 1},$$

or

$$\frac{1}{2} \ln \frac{\theta^2 + 1}{\theta^2 - 1}.$$

Accurately, as in the case of the symmetrical wave-filters, A_1 indicates the most essential part of the attenuation, but not the total attenuation as given by the Formula (1a).

From the manner of determining m and μ , by the T-parameters differing from the Tschebyscheff-parameters of the "Siebschaltungen", it follows that the computed minimum attenuation of a K-D-filter with T-parameters is somewhat smaller than half of the minimum attenuation of the corresponding symmetrical filters with Tschebyscheff-parameters. That difference amounts, at the most, to

$$\frac{1}{2} \ln 2 = 0.35 \text{ Napier}$$

(see also the following numerical example). After choosing a D-class and a W₁-class with their suitable parameters for a K-D-filter, where the parameters of the W₁-class may be chosen as Tschebyscheff-parameters according to the "Siebschaltungen" (the application of these parameters for the image-impedance classes of the K-D-filters is a feature of the present invention), Z_{11}, Z_{22} and Z_{12} are perfectly determined as the following functions of the frequency:

$$Z_{11} = W_1 D$$

$$Z_{22} = W_2 D$$

$$Z_{12} = R \sqrt{D^2 - 1}$$

In a manner analogous to the convention adopted in the case of symmetrical filters, the first member of a certain combination (D, W₁) will represent the attenuation, and the second member the image-impedance characteristic. For example, a filter of the class $\gamma/2$ signifies an HP-filter of constant determinant with D-characteristic $\gamma/2$ and image-impedance character-

istic 2. It will be understood that a K-D-filter of a certain class with that convention and with a certain

$$\sqrt{Z_{11}Z_{22}}$$

5 and

$$\sqrt{\frac{Z_{11}}{Z_{22}}}$$

10 shall comprise, in this specification as well as in the claims, not only the above-treated filters, but also the filters produced from these K-D-filters by combining them in series with an ideal transformer, as mentioned above, or representing an 15 equivalent network to such a series combination.

To construct a filter, it is further necessary to produce one of the many possible equivalent networks corresponding to the characteristic matrix

$$20 \begin{pmatrix} Z_{11}Z_{12} \\ Z_{12}Z_{22} \end{pmatrix}.$$

That matrix, derived in the manner just described, is always physically realizable. The partial-fraction-network represented by Fig. 2b 25 of the "Reaktanztheorem" is one kind of realization. A numerical example of filter design will be given, using the partial-fraction-network just mentioned, involving the HP-filter of constant determinant of the class $\gamma/2$, shown, with the numerical values of its circuit elements, in Fig. 3. The following technical requirements 30 may be prescribed: attenuation constant A_1 at least three Napiers up to a frequency of 860 per second, the nominal value of the image-impedance in the pass region beginning with the frequency 1100, 500 ohms, with a 5 percent deviation. The limiting frequency ω_1 shall be assumed as $2\pi \cdot 1000$ radian per second. As mentioned, the 35 parameters of class $\gamma/2$ are always T-parameters.

40 From Table I, for class $\gamma/2$

$$\sqrt{Z_{11}Z_{22}} = \frac{\sqrt{\lambda^2 + \omega_1^2}(\lambda^2 + \omega_\beta^2)}{\mu(\lambda^2 + \omega_\alpha^2)}$$

45 From Table II, it follows, for class 2 (HP):

$$\frac{\lambda\sqrt{\lambda^2 + \omega_1^2}}{m(\lambda^2 + \omega_\alpha^2)}$$

$$50 \quad \left[\begin{array}{l} \frac{0,812 \cdot 10^6 \cdot \lambda}{\lambda^2 + \omega_\alpha^2} + \frac{2,346 \cdot 10^6}{\lambda} + \frac{0,0380 \cdot \lambda}{\lambda^2 + \omega_\alpha^2} - 0,0362 \lambda \\ \frac{0,744 \cdot 10^6 \lambda}{\lambda^2 + \omega_\alpha^2} - 0,0362 \lambda \end{array} \right] \quad 50$$

By multiplication and division and multiplication with R , one obtains:

$$55 \quad (7) \quad Z_{11} = \frac{Rm}{\mu\lambda} \frac{\lambda^2 + \omega_\beta^2}{\lambda^2 + \omega_\alpha^2} (\lambda^2 + \omega_\alpha^2) = \frac{h_{11}^{(\alpha)}\lambda}{\lambda^2 + \omega_\alpha^2} + \frac{h_{11}^{(0)}}{\lambda} + h_{11}^{(\infty)}\lambda,$$

60 where

$$h_{11}^{(\alpha)} = \frac{Rm(\omega_\beta^2 - \omega_\alpha^2)(\omega_\alpha^2 - \omega_\alpha^2)}{\mu(-\omega_\alpha^2)};$$

$$h_{11}^{(0)} = \frac{Rm\omega_\beta^2\omega_\alpha^2}{\mu\omega_\alpha^2}; \quad h_{11}^{(\infty)} = \frac{Rm}{\mu};$$

$$65 \quad (8) \quad Z_{22} = \frac{R\lambda(\lambda^2 + \omega_1^2)(\lambda^2 + \omega_\beta^2)}{m\mu(\lambda^2 + \omega_\alpha^2)(\lambda^2 + \omega_\alpha^2)} = \frac{h_{22}^{(\alpha)}\lambda}{\lambda^2 + \omega_\alpha^2} + \frac{h_{22}^{(0)}\lambda}{\lambda^2 + \omega_\alpha^2} + h_{22}^{(\infty)}\lambda,$$

70 where

$$h_{22}^{(\alpha)} = \frac{R(\omega_1^2 - \omega_\alpha^2)(\omega_\beta^2 - \omega_\alpha^2)}{m\mu(\omega_\alpha^2 - \omega_\alpha^2)};$$

$$h_{22}^{(0)} = \frac{R(\omega_1^2 - \omega_\alpha^2)(\omega_\beta^2 - \omega_\alpha^2)}{\mu m(\omega_\alpha^2 - \omega_\alpha^2)}; \quad h_{22}^{(\infty)} = \frac{R}{m\mu}$$

according to (7) and (8), and taking into account the relation $Z_{11}Z_{22} - Z_{12}^2 = R^2$.

$$Z_{12} = \frac{h_{12}^{(\alpha)}\lambda}{\lambda^2 + \omega_\alpha^2} + h_{12}^{(\infty)}\lambda$$

where, according to (5),

$$h_{12}^{(\alpha)} = \pm \sqrt{h_{11}^{(\alpha)}h_{22}^{(\alpha)}}, \quad h_{12}^{(\infty)} = \mp \sqrt{h_{11}^{(\infty)}h_{22}^{(\infty)}}$$

In addition, it is desirable to choose also Tschebycheff-parameters for m and ω_α . As mentioned before, the parameters μ , ω_α , ω_β are T-parameters. According to Table XIV of the "Siebschaltungen", $\alpha^2 = 0.712$ corresponds to a 5 percent deviation of image-impedance in Class 2. From the third column of Table XI of the "Siebschaltungen", for Class 2,

$$m = H = 1.051$$

and

$$\omega_\alpha^2 = \alpha^2\omega_1^2 = 28.05 \cdot 10^6.$$

The value of $A_{1\min}$ of the corresponding symmetrical filter is

$$2(3 + \frac{1}{2} \ln 2) = 6.7 \text{ Napier},$$

resulting from the initial requirements of the problem. Corresponding to this value,

$$\kappa = \frac{1}{1.154}$$

is found in Table XIV of the "Siebschaltungen".

With this value κ , one finds, from Table III of this specification, or from Table XIV of the "Siebschaltungen",

$$\alpha^2 = \frac{1}{0.8600}, \quad \beta^2 = \frac{1}{0.3917}$$

From Table III,

$$\omega_\alpha^2 = \alpha^2\omega_1^2 = 45,9 \cdot 10^6,$$

$$\omega_\beta^2 = \beta^2\omega_1^2 = 100,8 \cdot 10^6,$$

$$\mu = \frac{\beta^2}{\alpha^2}\omega_1 = 13,8 \cdot 10^3,$$

$$\omega_1^2 = 39,45 \cdot 10^6$$

According to this, the characteristic matrix

$$\begin{pmatrix} Z_{11}Z_{12} \\ Z_{12}Z_{22} \end{pmatrix},$$

in partial-fraction development, becomes:

$$45 \quad \left[\begin{array}{l} \frac{0,812 \cdot 10^6 \cdot \lambda}{\lambda^2 + \omega_\alpha^2} + \frac{2,346 \cdot 10^6}{\lambda} + \frac{0,0380 \cdot \lambda}{\lambda^2 + \omega_\alpha^2} - 0,0362 \lambda \\ \frac{0,744 \cdot 10^6 \lambda}{\lambda^2 + \omega_\alpha^2} - 0,0362 \lambda \end{array} \right] \quad 50$$

Using the "Reaktanztheorem", the numerical values given in Fig. 3 will be obtained. It can be seen, from Figs. 4 and 5, that the technical requirements of the problem are fulfilled for the attenuation and the image impedance. Using Fig. 4, it is possible further to verify the property of the T-parameters mentioned above by this example. It follows:

$$\Omega_{\min} = \frac{\kappa}{\beta} = 0.542, \quad \Omega_\infty = \frac{\kappa}{\alpha} = 0.803,$$

and by the frequency transformation for HP:

$$\omega = \Omega\omega_1$$

one obtains:

$$\omega_{\min} = \Omega_{\min}\omega_1$$

or:

$$f_{\min} = \Omega_{\min}f_1 = 542 \text{ per second}, \quad f_\infty = 803 \text{ cycles per second.}$$

The infinite anti-resonance frequency, furthermore, of Z_{11} and Z_{22} corresponds to an infinite attenuation at $f = 0$.

This checks with Fig. 4.

The filter of Fig. 3 comprises two circuit branches. The first branch contains a condenser 1, and two coils 7, 8 in series between the input terminals 1, 1'. The second branch, between the output terminals 2, 2', contains a condenser 2 and a coil 3 in parallel, connected in series with two coils 4 and 5, a condenser 6 being disposed in parallel to the coil 5. The condensers and coils have the values indicated in Fig. 3. The coil 7 is coupled to the coil 4, and the coil 8 to the coil 5.

Two things should be noticed in connection with the network Fig. 3. First, it contains no ideal transformer, though, as the paper "Reaktanztheorem" demonstrates, ideal transformers cannot always be avoided in unsymmetrical, reactance, four-terminal networks. Secondly, it is to be noted that there is a circuit mesh connecting the input terminals 1, 1' and another circuit mesh connecting the output terminals 2, 2'; that these circuits are inductively coupled together by means of the coils, 4, 7 and 5, 8 respectively, above and below an intermediate point x ; and that the coupling of at least one pair of coils, the upper coils 4, 7, has the opposite sign to the coupling of at least one pair of coils, the pair of coils 8, 5 below. This opposite-sign coupling is indicated by the indication that the ratio 1:0.918 is positive and by the negative sign before the ratio 1:0.954, the former corresponding to the coils 8 and 5, and the latter to the coils 7 and 4. In some cases, of course, the coils 4 and 7, or 8 and 5, may be replaced by a single coil, common to the circuits through the input-terminals 1, 1' and the output terminals 2, 2'. The couplings of the network of Fig. 3, more especially, are tight. It is obvious, however, that untight couplings may be found in other, analogous K-D filters.

It is obviously impossible to describe in detail all the special applications of my invention. They will be understood by persons skilled in the art without further description. It is therefore desired that the appended claims be broadly construed, unlimited except insofar as limitations may be necessary to be imposed by the state of the prior art.

What I claim is:

1. A wave-filter network comprising a first terminal, a second terminal, a third terminal and a fourth terminal, a circuit connecting the first and the second terminals, a circuit connecting the third and the fourth terminals, the circuits being inductively coupled to one side and to the other side of an intermediate point, and an inductive coupling to the one side of the intermediate point being negative relative to an inductive coupling to the other side of the intermediate point, the image impedance at the first and the second terminals being the reciprocal of the image impedance at the third and the fourth terminals.

2. A wave-filter according to claim 1 that is unprovided with a practically ideal transformer.

3. A wave-filter according to claim 1 in which one of the coupled pair of coils is a single coil common to both circuits.

4. A wave-filter according to claim 1 in which the coupling is tight.

5. A filter network having two pairs of terminals, the image impedance at one of the pairs of terminals being the reciprocal of that at the other pair of terminals, characterized by the fact that the following conditions are satisfied: (a) that to each anti-resonance frequency of the open-circuit impedances in the pass-band or -bands a corresponding place of infinite attenuation can be re-

lated in that part of the attenuation band or parts of the attenuation bands in which the attenuation is to correspond at least to the predetermined value (T-interval or T-intervals), such that the product of the corresponding (normalized) frequencies is approximately equal to the limit of the T-interval expressed by normalized frequency; (b) that in the part of the pass-band or the parts of the pass-bands in which the image impedance has to have the predetermined value (Tschebyscheff-interval or -intervals) the minima or maxima of the image-impedance deviate from the predetermined value by an approximately equal amount, and that the products of the (normalized) frequencies of these minima and maxima with the corresponding resonance and anti-resonance frequencies of the open-circuit impedances in the attenuation-region or -regions are approximately equal to the normalized frequency of the limit of the Tschebyscheff-interval.

6. A filter comprising two pairs of terminals, a reactance network with mutual inductance between these terminals, the structure of said network not being separable in several impedance branches adapted to determine the characteristics of the filter, the image impedance at one of the pair of terminals being the reciprocal of the image impedance at the other pair of terminals, characterized by the fact that the following conditions are satisfied: (a) that the resonance and anti-resonance frequencies of the two open-circuit impedances of the network are coincident in the pass-band or -bands and are there closer and closer together as the limiting frequencies are approached; (b) that the resonance and anti-resonance frequencies of one of the open-circuit impedances are coincident respectively with the anti-resonances and resonances of the other open-circuit impedance in the attenuation-band or -bands and are there closer and closer together as the limiting frequencies are approached.

7. A filter network having two pairs of terminals, the image impedance at one of the pairs of terminals being the reciprocal of that at the other pair of terminals, characterized by the fact that the following conditions are satisfied: (a) that the minima of the product of both the open-circuit impedances are approximately equally high in that part of the attenuation band or parts of the attenuation bands in which the attenuation is to correspond at least to the predetermined value (T-interval or T-intervals) and that the places of these minima, expressed in terms of normalized frequency, are approximately given by the ratio of the limit of the normalized T-interval to the normalized resonance frequencies of the open-circuit impedances in the pass-band or -bands; (b) that the minima and maxima of the quotient of both the open-circuit impedances deviate with an approximately equal amount from the value one in that part of the pass-band or those parts of the pass-bands in which the image impedances have to have the predetermined value (Tschebyscheff-interval or -intervals), and that the places of said minima and maxima, expressed in terms of normalized frequency, are approximately given by the ratio of the limit of the normalized Tschebyscheff-interval to the normalized resonance (anti-resonance) and anti-resonance (resonance) frequencies of the one (the other) open-circuit impedance in the attenuation range, where the resonances of the one open-circuit impedance are the anti-resonances of the other and conversely.

8. A filter network having two pairs of termi-

nals, the image impedance at one of the pairs of terminals being the reciprocal of that at the other pair of terminals, characterized by the fact that the following condition is satisfied: that to each anti-resonance frequency of the open-circuit impedances in the pass-band or -bands a corresponding place of infinite attenuation can be related in that part of the attenuation band or parts of the attenuation bands in which the attenuation is to correspond at least to the predetermined value (T-interval or T-intervals), such that the product of the corresponding (normalized) frequencies is approximately equal to the limit of the T-interval expressed by normalized frequency.

9. A filter comprising two pairs of terminals, a reactance network with mutual inductance between these terminals, the structure of said network not being separable in several impedance branches adapted to determine the characteristics of the filter, the image impedance at one of the pairs of terminals being the reciprocal of the image impedance at the other pair of terminals, characterized by the fact that the following condition is satisfied: that the resonance and anti-resonance frequencies of the two open-circuit impedances of the network are coincident in the pass-band or -bands and are there closer and closer together as the limiting frequencies are approached.

10. A filter comprising two pairs of terminals, a reactance network with mutual inductance between these terminals, the structure of said network not being separable in several impedance branches adapted to determine the characteristics of the filter, the image impedance at one of the pairs of terminals being the reciprocal of the image impedance at the other pair of terminals, characterized by the fact that the following condition is satisfied: that the resonance and anti-resonance frequencies of one of the open-circuit impedances are coincident respectively with the

anti-resonances and resonances of the other open-circuit impedance in the attenuation-band or -bands and are there closer and closer together as the limiting frequencies are approached.

11. A filter network having two pairs of terminals, the image impedance at one of the pairs of terminals being the reciprocal of that at the other pair of terminals, characterized by the fact that the following condition is satisfied: that the minima of the product of both the open-circuit impedances are approximately equally high in that part of the attenuation band or parts of the attenuation bands in which the attenuation is to correspond at least to the predetermined value (T-interval or T-intervals) and that the places of these minima, expressed in terms of normalized frequency, are approximately given by the ratio of the limit of the normalized T-interval to the normalized resonance frequencies of the open-circuit impedances in the pass-band or -bands. 20

12. A filter network having two pairs of terminals, the image impedance at one of the pairs of terminals being the reciprocal of that at the other pair of terminals, characterized by the fact that the following condition is satisfied: that the 25 minima and maxima of the quotient of both the open-circuit impedances deviate with an approximately equal amount from the value one in that part of the pass-band or those parts of the pass-bands in which the image impedances have to 30 have the predetermined value (Tschebyscheff-interval or -intervals), and that the places of said minima and maxima, expressed in terms of normalized frequency, are approximately given by the ratio of the limit of the normalized Tschebyscheff- 35 interval to the normalized resonance (anti-resonance) and anti-resonance (resonance) frequencies of the one (the other) open-circuit impedance in the attenuation range, where the resonances of the one open-circuit impedance are 40 the anti-resonances of the other and conversely.

WILHELM CAUER.
